UNITED STATES PATENT OFFICE.

F. WILLSON ROGERS, OF HARTFORD, CONNECTICUT.

DESIGN FOR SPOON AND FORK HANDLES.

Specification forming part of Design No. **11,431**, dated September 23, 1879; application filed August 26, 1879.
[Term of patent 7 years.]

To all whom it may concern:

Be it known that I, F. WILLSON ROGERS, of Hartford, in the county of Hartford and State of Connecticut, have invented and produced a new, original, and useful Design for a Spoon or Fork Handle, of which the following is a specification.

In the accompanying cut is shown, in plan view, a spoon having a handle ornamented with the present design, to be known as the "Hartford."

Referring to this cut, A is any ordinary spoon, and of any desired size. Its handle B is toward the end b of a general oval shape, with suitable lines c near the border, on the face surrounding the plain space b', and at the extreme end of the handle the inner line waves downward a little, and affords a small triangular space at c' for ornamentation. Inside these lines is a band of lozenge-shaped figures, d, the lower ends terminating below a band, e, which runs obliquely across the face of the handle. On the center of this band is a row of circles, e', in each of which is a star-shaped figure.

Just above the band, and pointing upward on the oval-shaped space aforesaid, is a spray of flowers, g, its stem showing a little below said band. Farther down the handle next

comes an ornamentation, h, of lattice-work or crossed lines, and beneath this are the ovoid shapes or ornamentations i, resting below on several lines or bands, k, and below is a loop, l, extending toward the shank of the spoon.

While this ornamentation of the handle is now shown on a spoon, it is evident that it can be used equally well on a fork-handle.

Having thus described my invention, what I consider new, and desire to secure by Letters Patent, is—

1. The design for a spoon or fork handle, consisting of the lines c, band d, and spaces b' and c', with band e, ornamented as desired, lattice-work h, ovoid shapes i, band k, and loops l, substantially as shown and described.

2. The design for a spoon or fork handle, consisting of the end b, having border-lines c and band of diamond or lozenge shapes d, and space b', with the flower g and oblique band e, having ornament e', substantially as described.

In testimony that I claim the foregoing as my own I affix my signature in presence of two witnesses.

F. WILLSON ROGERS.
